US0D1036405S

(12) **United States Design Patent** (10) **Patent No.:** **US D1,036,405 S**
(45) **Date of Patent:** ** *Jul. 23, 2024

(54) **HANDHELD COMMUNICATION DEVICE**

(71) Applicant: **MOTOROLA MOBILITY LLC**,
Chicago, IL (US)

(72) Inventors: **James Sloss**, Glenview, IL (US);
Ruben Castano, Glenview, IL (US)

(73) Assignee: **Motorola Mobility LLC**, Chicago, IL
(US)

(*) Notice: This patent is subject to a terminal disclaimer.

(**) Term: **15 Years**

(21) Appl. No.: **29/738,926**

(22) Filed: **Jun. 21, 2020**

(57) **CLAIM**

The ornamental design for a handheld communication device, as shown and described.

DESCRIPTION

FIG. 1 is a front perspective view of a handheld communication device;

FIG. 2 is a rear perspective view of the first embodiment thereof;

FIG. 3 is a front view of the first embodiment thereof;

FIG. 4 is a rear view of the first embodiment thereof;

FIG. 5 is a first side view of the first embodiment thereof;

FIG. 6 is a second side view of the first embodiment thereof;

FIG. 7 is a top view of the first embodiment thereof; and,

FIG. 8 is a bottom view of the first embodiment thereof.

The broken lines in the drawings illustrate portions of the handheld communication device that form no part of the claimed design.

1 Claim, 6 Drawing Sheets
